J. Darling,

Steam-Boiler Water-Tube.

N° 66,683.

Patented July 16, 1867.

Jeremiah Darling

United States Patent Office.

JEREMIAH DARLING, OF CINCINNATI, OHIO.

Letters Patent No. 66,683, dated July 16, 1867.

IMPROVEMENT IN STEAM-GENERATORS.

The Schedule referred to in these Letters Patent and making part of the same.

TO ALL WHOM IT MAY CONCERN:

Be it known that I, JEREMIAH DARLING, of the city of Cincinnati, Hamilton county, State of Ohio, have invented a new and improved Steam-Boiler; and I do hereby declare the following to be an exact description thereof, reference being had to the accompanying drawings, and to the letters of reference marked thereon, making a part of this specification.

The nature of my invention consists in the arrangement and construction of posts supporting a dome or boiler at top, the posts or columns containing water and steam, with water and steam pipes connected with the posts and the dome and fire-place underneath, the whole forming a safe steam-boiler.

Figure 1 represents a side elevation of the improved steam-boiler.

Figure 2, a cross-section of the same.

Figure 3 exhibits one of the octagon-shaped columns or posts containing water and steam, and forming each corner of the fire-box, and supporting the steam-dome or boiler at top. This column has pipes attached, whose ends are tapering, as seen at fig. 7; and there are two such columns located diagonally to each other across the fire-box.

Figure 4 exhibits a similar column, but having the pipes with screw-ends (not tapering) attached. There are two of these columns or posts, fig. 4, also located diagonally across the fire-box and likewise supporting the dome.

Figure 5 shows the shape or elbow-top of the column or post, and its position as attached to the dome.

Figure 6 represents the octagon shape of each column or post as attached to the elbow, when looking at it upside down.

Figures 7 and 8 represent the side and end horizontal pipes forming the fire-box and attached to the columns or posts, fig. 7, having one end smooth and tapering, so as to fit in the smooth socket of fig. 3, while the other end has a screw-thread to screw into, fig. 4; and fig. 8 has screw-threads on both ends, cut right and left, to fit into both posts, as shown in figs. 3 and 4.

A represents the fire-place; B the grate; C the steam-dome or boiler; D the smoke-stack; E the steam pipe; G G are the four posts or columns that support the dome, and in which the pipes are inserted and form the fire-box. Four or more posts may be used if necessary. The outside pipes H, as shown at fig. 8, have screw-threads at their ends, one a right and the other a left-hand screw, for the purpose of drawing the posts G tight together upon the pipe J that is tapered at one end, said pipe J being first screwed into the opposite post G, and the tapering end fitting itself tightly into the smooth socket of the other post G as the posts are being screwed together. To make the pipes perfectly tight, to prevent leakage, the loose pipes J are screwed back until the tapering ends are pressed up to their bearing in the opposite post G, which makes both ends tight. Inside of the outside pipes, and inside of the fire-box, over the fire, are coils of extra pipes, K, four, more or less, that connect with or start from the posts G, inclining upward and connecting with the posts G or with the steam-dome C above, on the sides of the dome. Other pipes L start from and out of posts G, and also enter the sides of the steam-dome C.

The water passes from the posts G, at either end of the horizontal pipes J and H, (according to the horizontal position of the boiler,) during the rocking motion of the boiler, the water passing in the pipes at the lower end and the steam out at the upper end. The water is first put into the steam-dome C, and from thence fills the columns G; or the water may be forced into the columns G, or into any of the pipes, to supply the boiler.

One advantage gained is, that my short pipes will not blow out dry and leave them subject to burn, as frequently occurs with long pipes or coils heretofore used. Another advantage is, my inside pipes inclining upwards are not affected by any rocking motion of the boiler. Another advantage is, that my dome, being of small diameter and greater distance from the fire, is less liable to explosion than larger boilers; and at the same time I have a small dome and larger boiler, by the use of my pipes, concentrated over the fire, as arranged and combined with the columns G, and requiring much less room, less fuel, and less fire-place to make the same amount of steam.

M are blow-off cocks attached to the steam and water columns G for the purpose of cleaning the columns when necessary.

What I claim as new, and desire to secure by Letters Patent, is—

1. The steam and water columns G, when constructed and arranged as and for the purposes set forth.
2. I also claim the pipes J, when arranged with reference to the columns G as herein described and for the purposes set forth.
3. I also claim the coil or incline pipes K, when arranged and combined with the posts G and dome C, as herein described and for the purposes set forth.

JEREMIAH DARLING.
